 The National Cash Register Company, Dayton,
 Ohio, a corporation of Maryland

Application March 5, 1941, Serial No. 381,781

9 Claims. (Cl. 235—8)

The present invention relates to improvements in cash registers and accounting and analogous business machines, and is particularly directed to improvements in the latches for the differential mechanisms of machines of the type disclosed in Letters Patent of the United States No. 1,619,796, No. 1,747,397, and No. 1,761,542, issued, respectively, March 1, 1927, February 18, 1930, and June 3, 1930, to B. M. Shipley.

Broadly it is an object of this invention to provide an improved latch mechanism for the differential devices of machines of the character referred to above.

A more specific object is the provision of positive-acting latch mechanisms for the differential devices of machines of the character referred to above, said latch mechanisms also being provided with an easy unlatching action to facilitate the positioning of the differential devices.

Another object is to provide the differential mechanisms of machines of the character referred to above with improved latch mechanisms which positively lock said differential mechanisms to their driving means, said latch mechanisms, although positive, adapted to be unlatched with a minimum of mechanical effort, to facilitate the positioning of the differential mechanisms under influence of the depressed amount keys or the totalizer wheels.

With these and incidental objects in view, the invention includes certain novel features of construction and combinations of parts, the essential elements of which are set forth in appended claims, and a preferred form or embodiment of which is hereinafter described with reference to the drawing which accompanies and forms a part of this specification.

In the drawing:

Fig. 1 is a fragmentary side elevation, as observed from the right of the machine, showing the differential mechanism for one denominational order and the improved latch mechanism therefor, said parts being shown in home position.

Fig. 2 is a top plan view of a part of the mechanism shown in Fig. 1.

Fig. 3 is a detail view, partially sectioned, showing the side spacing of the different parts of the improved latch mechanism.

Fig. 4 is a side elevation, similar to Fig. 1, but showing the differential mechanism and the improved latch mechanism after they have been positioned under influence of a depressed amount key.

Fig. 5 is a side elevation, as observed from the

right of the machine, showing in detail the structure of the improved latch mechanism.

Description

The present invention is directed to an improved latch mechanism for latching the differential devices of machines of the type disclosed in the Shipley patents referred to hereinbefore to their driving mechanisms. The problem in connection with differential latches of this nature always has been to provide a latch which forms a safe operating connection between the differential mechanisms and their driving segments, and, in addition, said latch should have an easy unlatching action, so that it may be unlatched with a minimum of mechanical effort, in order to insure the proper positioning of the differential mechanisms under influence of the depressed amount keys or under influence of the totalizer wheels.

The present invention satisfactorily solves the above problem by providing a latch mechanism which positively connects the differential mechanism to its driving segment, said positive connection being formed by a blocking means that normally blocks disengaging or unlatching movement of the latch. The latch blocking means moves in unison with the differential mechanism and remains effective during the positioning movement of said differential mechanism and until further movement of one portion of said blocking means is obstructed either by a depressed key or by the long tooth on the corresponding totalizer wheel. This obstructing of the movement of one portion of the blocking means permits the other portion to move independently thereof until the two blocking portions are disengaged from each other. The disengaging of the blocking portions unlocks the latch mechanism, whereupon camming surfaces formed on the driving segment and the portion of the latch engaged therewith force said latch to disengaged position to position the differential mechanism in proportion to the depressed amount key or the corresponding totalizer wheel.

Only the portion of the differential mechanism necessary for the proper explanation of the improved latch mechanism has been disclosed herein, and further disclosure is believed unnecessary, as reference may be had to the Shipley patents mentioned above for a full showing and explanation of this standard type of differential mechanism, which, through prolonged usage, has become well established in the art.

Referring to Figs. 1 to 5 inclusive of the draw-

ing, the differential mechanism for one denominational order comprises a differential actuator 28 carrying a hub 21, which is rotatably supported by a bushing 22 extending between right-hand and left-hand differential support plates (not shown) in turn supported on rods (not shown) extending between the main framework of the machine. A tie rod 23 passes through a boring in the center of the bushing 22 to secure the differential mechanisms for the different denominational orders in an integral unit. The actuator 28 comprises right and left plates 24 and 25, between which are secured a plurality of gear segments 26, which actuate the corresponding totalizer wheels on the various totalizer lines. Also secured between said plates 24 and 25 is a differential latch support plate 27.

The plates 24, 25, and 27 (Figs. 1, 3, 4, and 5) have secured therein studs 28 and 29, the stud 28 rotatably supporting a bushing 30 secured in an arm 31 and the stud 29 having journaled thereon an arm 32. The upper ends of the arms 31 and 32 are pivotally connected to a differential latch 33 and support said latch for parallel shifting movement. A spring 34 (Fig. 1), tensioned between the latch 33 and the actuator 28, urges said latch rearwardly to normally maintain an angular camming surface 35 on a foot-shaped extension thereof in engagement with a similar camming surface 36 on a differential driving segment 37 free on the bushing 22.

A link 38 operatively connects the segment 37 to an operating mechanism, not here shown but similar in every respect to that shown for the differential driving segment 365 in Fig. 8 of the Shipley Patent No. 1,619,796. The operating mechanism for the segment 37, including a cam lever connected to the link 38 and companion plate cams, imparts an invariable oscillating movement to said segment 37 each machine operation, the first movement being in a clockwise direction.

The circumferential surface of the hub 30 (Figs. 3 and 5) rotatably supports a hub 38 secured in an arm 40 carrying a stud 41, which extends through a notch 42, formed by the bifurcated forward end of the plate 27, and thence into a slot 43 in a forward extension of a latch-operating spider 44 free on the hub 21. A spring 45 (Fig. 1), tensioned between the plate 27 and the spider 44, urges said parts counter-clockwise and clockwise, respectively, to cause the slot 43 in said spider, in cooperation with the stud 41, to urge the arm 40 clockwise to normally maintain said stud 41 in engagement with the upper surface of the notch 42, which notch is adapted to limit the rocking movement of said arm 40 in either direction. The arm 40, the stud 41, the notch 42, the slot 43, and the spring 45 form a yieldable lost-motion connection between the actuator 28 and the spider 44.

When the differential mechanism is in home position, as shown in Fig. 1, the spring 45 maintains the actuator 28 and the spider 44 in the relative positions here shown, in which positions a projecting finger 46 on said spider 44 is maintained in the path of a flat surface on a stud 47 secured in the lower end of the arm 31 (Figs. 1, 3, and 5) to form a positive obstruction against counter-clockwise movement of said arm and disengaging movement forwardly, or toward the left, of the latch 33. This insures that the camming surface 35 on said latch is maintained in engagement with the camming surface 36 to form a positive driving connection between the differ-

ential mechanism and the driving segment 37.

The arm 40 (Figs. 1, 4, and 5) has thereon a rounded surface 48 adapted to engage the lower end of the stem of any one of a series of depressible amount keys 49 for this particular order, when such amount key is depressed. The amount keys 49 are mounted in a key framework similar to that shown in Fig. 8 of the Shipley Patent No. 1,619,796.

Depressing any one of the amount keys 49 moves the lower end of the stem thereof into the path of the rounded surface 48, as shown in Fig. 4, and, upon machine operation, the driving segment 37, during its initial movement clockwise and through the connection formed by the latch 33, carries the differential actuators 28 and the spider 44 clockwise in unison therewith until the surface 48 moves into engagement with the stem of the depressed key 49. This immediately arrests clockwise movement of the spider 44. However, the lost-motion connection formed by the stud 41 and the notch 42 in the plate 27 permits the differential actuator 28 to move clockwise independently of the spider 44 until the stud 47 is moved upwardly out of the path of the projecting finger 46. Immediately after the stud 47 has moved out of the path of the finger 46, the stud 41 in the arm 40 contacts the lower surface of the notch 42 to prevent further clockwise movement of the actuator 28, whereupon the camming surface 36 on the segment 37, in cooperation with the similar surface 35 on the foot of the latch 33, forces said latch forwardly against the action of the spring 34 to disconnect said actuator 28 from the driving segment 37 and to simultaneously engage a foot-shaped forward extension 50 (Figs. 1, 4, and 5) of said latch with the corresponding one of a series of alining notches 51 in an alining plate 52 supported in the usual manner by the left-hand differential hanger plate. During forward disengaging movement of the latch 33, the stud 47 moves into a clearance recess 53, as shown in Fig. 4.

After the actuator 28 has thus been positioned, the segment 37 continues its clockwise movement without interruption, causing an arcuate surface 54 thereon to pass opposite the sole of the foot-shaped right-hand extension of the latch 33 to lock said latch in the corresponding notch 51 to prevent displacement of said actuator 28.

The amount keys 49 are used only in adding and subtracting operations, and, in such operations, after the segment 37 has completed its initial movement clockwise, the corresponding wheel of the selected totalizer is engaged with the corresponding set of teeth 26 on the actuator 28. During return movement counter-clockwise of the segment 37, the arcuate surface 54 moves out of the path of the sole of the foot-shaped extension of the latch 33, and the angular shoulder formed on the periphery of said segment by the camming surface 36 moves opposite the corresponding surface 35, whereupon the spring 34 immediately shifts said latch 33 rearwardly, or towards the right, to engage the camming surfaces 35 and 36 and to move the stud 47 beyond the finger 46. Immediately thereafter, the spring 45 moves the spider 44 clockwise to again place the projection 46 in the path of the stud 47, as shown in Fig. 1, to form a positive driving connection between the actuator 28 and the segment 37. Simultaneously with the engaging of the surfaces 35 and 36, a shoulder 55 (Figs. 1 and 4) on the segment 37 engages a stud 56 carried by the actuator 28 and returns said actuator

counter-clockwise in unison therewith to home position, as shown in Fig. 1. The return movement counter-clockwise of the actuator 20 is proportionate to the value of the depressed amount key 49, and such movement rotates the engaged totalizer wheel a like distance to enter therein an amount corresponding to the value of said depressed amount key.

It will be recalled that relative movement of the actuator 20 and the spider 44 is determined by the notch 42 in the forward end of the plate 27 in cooperation with the stud 41. When the differential mechanism is in normal or home position, as shown in Fig. 1, the spring 45 retains the stud 41 in engagement with the upper surface of said notch 42, and, when said latch 33 is disengaged from the drive segment 37, as shown in Fig. 4, said stud engages the lower surface of said notch 42.

In adding and subtracting operations when no amount key 49 is depressed, a zero stop pawl, not shown here but well known in the art and illustrated in Fig. 8 of the Shipley Patent No. 1,619,796, engages the forward extension of the spider 44 to disengage the latch 33 in exactly the same manner as the depressed amount key 49 disengages said latch, to locate the actuator 20 in zero position.

In adding and subtracting operations, the segment 37 (Figs. 1 and 4) receives one excursion of movement, as explained above, and, in sub-total and total printing operations, said segment receives two such excursions of movement, the first of these excursions being an idle movement, which occurs while the interspersed totalizers are being shifted laterally to select the desired set of wheels thereon. During the idle movement of the segment 37, the zero stop pawl disengages the latch 33 in zero position, and, prior to the beginning of the second excursion of movement of said driving segment 37, the zero stop pawl for this particular order is rocked out of the path of the forward end of the spider 44, and, at the same time, the corresponding wheel of the selected totalizer is moved into engagement with the corresponding teeth 26 of the actuator 20. Initial movement clockwise of the actuator 20, under influence of the segment 37, causes the teeth 26 to reversely rotate the corresponding wheel of the selected totalizer until a long tooth on said wheel rocks an obstruction, not shown here but fully disclosed in the above-mentioned Shipley patents, into the path of the corresponding one of a series of internal teeth 57 on the spider 44 to position said spider in proportion to the amount on said totalizer wheel.

This termination of the clockwise movement of the spider 44 by means of the slot 43 in cooperation with the stud 41 (Figs. 1 and 4) disengages the latch 33 in exactly the same manner as the amount keys 49 disengage said latch in adding and subtracting operations, to position the actuator 20 in proportion to the amount standing on the selected totalizer wheel. The usual beam mechanism transmits the positioning of the actuator 20 in adding, subtracting, and sub-total and total printing operations to the printing mechanism to cause the amounts to be recorded.

The long tooth of the selected totalizer wheel corresponds to the zero position of said wheel; consequently, the actuator 20 reversely rotates said wheel from its set position to zero position. In total printing operations, the selected totalizer wheel is disengaged from the corresponding teeth

26 prior to return movement counter-clockwise of the actuator 20, and consequently said wheel remains in a zeroized condition. In sub-total printing operations, the selected totalizer wheel remains in engagement with the corresponding teeth 26 during return movement counter-clockwise of the actuator 20 and is therefore restored to its original position.

Summarizing briefly, it will be seen, by referring to Figs. 1 and 2, that the projecting finger 46 on the spider 44, in cooperation with the stud 41, forms a positive locking connection between the latch 33 and the driving segment 37, which connection can only be unlocked or broken by the interruption of clockwise setting movement of said spider 44, either by a depressed amount key 49 in adding and subtracting operations or by means of the long tooth of the selected totalizer wheel in sub-total and total printing operations. This positive locking of the latch 33 prevents any interference with the clockwise movement of the actuator 20, either from frictional drag or from minor obstructions, from prematurely disengaging said latch 33 and effecting an erroneous positioning of said actuator 20. While the latch 33 is positively locked against accidental disengagement, still the novel structure of this improved mechanism permits said latch to be disengaged under influence of the depressed amount key or the selected totalizer wheel, in the manner explained above, with the expenditure of a minimum amount of mechanical effort, such effort being much less than that required for the disengaging of former latches of conventional construction. In fact, after the stud 41 moves above the projection 46, the camming surfaces 35 and 36 assist in the disengaging of the latch 33 instead of retarding such disengaging, due to frictional drag, as was the case with former latches, in which the connecting surfaces formed a locking connection rather than a camming connection.

Therefore, it is believed that it is too obvious for further elaboration that the above specification discloses a novel latch mechanism which forms a positive driving connection between the differential mechanism and its driving means, which mechanism at the same time is easily disengaged or unlocked when the differential mechanism arrives in selected position, and that said improved latch mechanism, due to its many novel features of construction and operation, constitutes a substantial advancement in the art.

While the form of mechanism herein shown and described is admirably adapted to fulfill the objects primarily stated, it is to be understood that it is not intended to confine the invention to the one form or embodiment disclosed, for it is susceptible of embodiment in various forms all coming within the scope of the claims which follow.

What is claimed is:

1. In a device of the class described, the combination of a driving member; a driven member; a latch carried by the driven member and coacting with the driving member to connect the driven member to the driving member; means yieldably connected to the driven member to block the latch against unlatching movement and; means to arrest motion of the blocking means, as the driven member continues to move, to unblock the latch, said driving member effective after the latch is unblocked to move said latch to disconnect the driven member from the driving member.

2. In a device of the class described, the combination of a driving member; a driven member; a latch to connect the driven member to the driving member; means carried by the driven member to shiftably support said latch on the driven member; a projection on the connecting means; an element adapted to cooperate with the projection to normally obstruct the latch against unlatching movement; a yieldable connection between the element and the driven means; and means to arrest motion of the element whereupon the yieldable connection permits the driven member to move after the element has been arrested to move the projection out of cooperative relationship with said element, said driving member effective after the projection has been moved out of cooperative relationship with the element, to move the latch to disconnect the driven member from the driving member to position said driven member commensurate with the position of the element.

3. In a device of the class described, the combination of a driving member; a driven member; a latch to connect the driven member to the driving member; means, including companion arms mounted on one of said members, to shiftably support the latch; a projection on one of the companion arms; an element normally movable in unison therewith a yieldable connection between the element and the driven member whereby the two members are normally actuated in unison; a prominence on the element adapted to cooperate with the projection to normally retain the latch in latching position; and means to arrest motion of the element, said yieldable connection permitting the driven member to move after the element has been arrested to thereby cause the projection to move out of cooperative relationship with the prominence, said driving member and said latch having camming surfaces, effective upon continued movement of the driving member after the projection has moved out of cooperative relationship with the prominence, to move said latch to disconnect the driving member from the driven member.

4. In a device of the class described, the combination of a driving member; a driven member; a latch to connect the driven member to the driving member; means to shiftably mount said latch on the driven member; a projection on the mounting means; an element adapted to cooperate with the projection to normally block the latch against unlatching movement; a lost-motion connection between the driven member and the element; yieldable means to take up the lost motion in one direction; and means cooperating with the element to arrest movement thereof whereupon the lost-motion connection and the yieldable means permit the driven member to move after said element has been arrested to move the projection out of cooperative relationship therewith, said driving member effective after the projection moves out of cooperative relationship with the element, to move the latch to disconnect the driven member from the driving member to position said driven member commensurate with the element and the arresting means.

5. In a device of the class described, the combination of a driven member; a driver to drive the driven member; a latch mechanism shiftably mounted on the driven member; coacting surfaces on the latch mechanism and the driver adapted to form an operating connection therebetween; an element yieldably connected to the

driven member, said element adapted to cooperate with the latch mechanism to normally retain the coacting surfaces in engagement with each other; and means to arrest the element after it has completed various extents of movement whereupon the driven member, due to the yieldable connection, moves a fixed distance after said element has been arrested to move the latch mechanism out of cooperative relationship with said element to permit the coacting surfaces to shift the latch to ineffective position to disconnect the driven member from the driver to position said driven member commensurate with the element and the arresting means.

6. In an accounting machine, the combination of a differential device adapted to be positioned to correspond to different numerical values; means to drive the differential device; latch means carried by the differential device and coacting with the said device to connect said device to the driving means; an element movable in unison with said device, said element contacting the latch means to normally obstruct unlatching movement of the latch means; a yieldable connection between the said device and element; and means to arrest movement of the element to position said element commensurate therewith, whereupon the yieldable connection permits the differential device to move said element a sufficient distance to move the latch out of obstructing relationship with said element; after the element has been arrested, said driving member effective after the latch has been unobstructed to move said latch to position the differential device commensurate with the element and the arresting means.

7. In an accounting machine having a differential device comprising a driven member and a driving member, the combination of a latch mechanism to connect the driven member to the driving member, said latch mechanism shiftably mounted on said driven member; an element; coacting projections on the latch mechanism and the element; yieldable means to connect the element to the driven member, said yieldable means adapted to urge the driven member and the element in opposite directions to normally maintain the projections in coacting relationship with each other to block unlatching movement of said latch; a stop; means cooperating with the stop to arrest movement of the element, whereupon the yieldable means permits the driven member to continue movement after said element is arrested to move the projection on the latch mechanism out of coacting relationship with the projection on the element; and camming surfaces on the latch mechanism and the driving member, effective when the projections are moved out of coacting relationship with each other, to move the latch mechanism to disconnect the driven member from the driving member to position said driven member commensurate with the arrested position of the element and of the position of the stop.

8. In a machine of the character described, having a differential device comprising a positionable driven member and a driving member therefor, the combination of a latch to connect the driven member to the driving member; means, including companion arms, to shiftably mount the latch on the driven member; an element; means to form a lost-motion connection between the element and the driven member; a projection on one of the companion arms; a pro-

jection on the element arranged to cooperate with the other projection to block unlatching movement of the latch; yieldable means to take up the lost motion between the element and the driven member to normally maintain the projections in cooperative relationship with each other; means to arrest the element, whereupon the yieldable means and the lost-motion connection permit the driven member to move relatively to said element to move the projection on the arm out of cooperative relationship with the other projection to free the latch for unlatching movement; and coacting camming surfaces on the latch and the driving member, effective when the projections are moved out of cooperative relationship, to move the latch to disconnect the driven member from the driving member to in turn position said driven member commensurate with the position of the element and of the position of the arresting means.

9. In a machine of the class described, having a differential device comprising a driven member and a driver to drive the driven member, the combination of a latch to connect the driven member to the driver; companion arms to shiftably support the latch on the driven member; coacting surfaces on the latch and the driver; a first yieldable means to urge the coact-

ing surfaces into engagement with each other to form an operating connection between the driven member and the driver; an element; means to form a lost-motion connection between the element and the driven member; a projection on one of the companion arms; a projection on the element adapted to cooperate with the other projection to retain the coacting surfaces in engagement with each other to form a positive operating connection between the driven member and the driver; a second yieldable means to take up the lost motion between the element and the driven member to normally maintain the projections in cooperative relationship with each other; and means to stop the element after it has completed an extent of movement, after which the lost-motion connection and the second yieldable means permit the driven member to move a fixed distance, after said element is arrested, to move the projection on the arm out of cooperative relationship with the other projection to free the latch for shifting movement, whereupon the coacting surfaces shift said latch to disconnect the driven member from the driver to position said driven member commensurate with the arrested position of the element and the stopping means.

LAURENCE N. LEHMAN.
